[57] **CLAIM**

The ornamental design for a cleaning tool for ceiling fan blades, as shown and described.

DESCRIPTION

FIG. 1 is a perspective view of a cleaning tool for ceiling fan blades, showing my new design;

FIG. 2 is a perspective view as seen from the end opposite that shown in FIG. 1;

FIG. 3 is a front elevational view, the rear being a mirror image thereof;

FIG. 4 is a side elevational view thereof, as seen from the left side of FIG. 3;

FIG. 5 is a side elevational view thereof, as seen from the right side of FIG. 3;

FIG. 6 is a top plan view thereof; and

FIG. 7 is a bottom plan view thereof.
